UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTONHOLE-SEWING MACHINE.

1,277,588.

Specification of Letters Patent. Patented Sept. 3, 1918.

Original application filed February 10, 1912, Serial No. 676,767. Divided and this application filed April 29, 1913. Serial No. 764,377.

To all whom it may concern:

Be it known that I, GEORGE S. HILL, a citizen of the United States, residing at Strafford, in the county of Strafford and State of New Hampshire, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines of that class in which a work holding clamp and a stitch forming mechanism are relatively movable to form over-edge stitches extending along the sides and about the ends of the buttonhole.

The present application is a division of application No. 676,767, filed February 10, 1912, for buttonhole sewing machines.

The object of the invention is to provide novel and improved mechanism for opening and closing the work holding clamps of machines of the above type, and to that end the invention comprises the features of construction and combinations of parts hereinafter described and set forth in the claims.

The various features of the invention will be understood from an inspection of the accompanying drawings and the following detailed description of the machine illustrated therein.

In the drawings:

Figure 1 is a front elevation of a buttonhole sewing machine embodying the features of the invention in their preferred forms;

Fig. 2 is a side elevation, partly in section;

Fig. 3 is a sectional plan view, the section being taken below the head of the machine;

Fig. 4 is a detail vertical sectional view showing the parts which operate upon the work.

The machine illustrated comprises generally a work clamp for holding the material to be operated upon, a cutter for cutting a buttonhole in the material, stitch forming mechanism comprising a straight-eye-pointed upper needle, a curved-eye-pointed under needle, and a coöperating looper, and mechanisms for operating the clamp, cutter, and stitch forming mechanism and for relatively moving them to prop-

erly position the material for cutting and then sewing the buttonhole, and for relatively feeding and turning the clamp and stitch forming mechanism during the operation of the stitch forming mechanism to form over-edge stitches extending along the sides and about the ends of the buttonhole. The relative movements referred to are secured in the machine illustrated by movement of the work clamp and by turning the stitch forming mechanism.

The operative parts of the machine shown in the drawings are carried by a frame 1 supported on a base 2 to which the frame is connected by trunnions 3 so that it may be swung up to give access to the parts on its under side which are normally inclosed and protected by the base. The work clamping devices comprise work supporting plates 4 arranged to pass on opposite sides of the stitch forming mechanism and connected to the clamp carriage 5 by the pivot screws 6. The work is clamped on the plates 4 by clamping jaws 7 pivoted on the ends of the clamp carrying arms 8. The clamp arms are pivotally supported in blocks 9 which are provided with ribs engaging grooves in the plates 4, and are held in adjusted position on the plates by the clamping screws 11 which pass through slots in the blocks. The work supporting plates 4 are forced normally toward each other by the spring-pressed bars 12 which are mounted in supports 13 rising from the clamp carrier 5, and are provided with depending ends engaging grooves in the plates. When the machine is at rest the parts are in the position indicated in Fig. 2 with the clamps 7 open to receive the material and to position it in proper relation to the buttonhole cutting devices. After the material is placed between the clamps and the work supporting plates 4, and the machine is started, the cutting devices are operated to cut the buttonhole. The movement of the cutter is also utilized to close the work holding clamps, thus simplifying the clamp operating devices and reducing the number of operating cams. After the buttonhole is cut and the work clamped, the clamp carriage is moved forward to bring the buttonhole into proper relation to the stitch forming mechanism.

The devices for cutting the buttonhole

comprise a lower cutter block 22 which is supported upon the front end of a tongue 23 projecting forward from a block 19 secured to the turret bracket 21, and a cutter blade 5 or die 24 secured in the end of an arm 25 which projects forward from a yoke 26. The ends of the yoke are pivotally supported on trunnions 27 carried by lugs 28 rising from the frame 1 (Figs. 1 and 3). A lever 10 29 is pivoted to the rear side of the yoke, and one end of this lever is arranged to engage a cam 30 formed on the upper surface of the cam carrying gear 31. The other end of the lever bears against a set screw 32 15 on the yoke, which may be adjusted to bring the cutter into proper operative relation with the under cutter block when the end of the lever 29 rides on to the high part of the cam 30. The tongue 23 and cutter block 20 22 are firmly supported during the action of the cutter by a plate 23' which is secured to the top of the under-needle turret.

The devices for operating the work holding clamp comprise arms 33 carried by a 25 rock shaft 34 and engaging slots 35 in the clamp arms 8 (Figs. 1, 3 and 4). The rock shaft 34 is mounted in bearings formed in the supports 13 on the clamp carriage, and is forced in a direction to open the clamp by 30 a torsional spring 36, one end of which is engaged with one of the supports 13, and the other end of which engages an arm 37 extending vertically from the rock shaft. The upper end of the arm 37 carries an adjustable screw 38, the end of which engages a bearing block 39 on the cutter yoke 26 when the work clamp is in position to receive the work. When the cutter is operated, the movement of the yoke 26 moves the arm 40 37 forward, thus rocking the rock shaft 34 in a direction to close the work clamp. After the work clamp has been thus closed it is held closed until the sewing of the buttonhole is completed and the clamp moved 45 into position for the removal of the work preparatory to the next cycle of operations. The devices for holding the clamp closed comprise a spring-pressed latching pin 40 mounted in a vertical projection on the hub 50 of one of the arms 33 and arranged to engage a shoulder 41 on one of the supports 13 (Fig. 4). The shoulder 41 is formed at the lower end of a bearing 42 in which a spring-pressed latch operating pin 43 is 55 mounted to move vertically. The latch operating pin is provided at its upper end with a V-shaped head 44 arranged to coöperate with a stationary cam 45. The cam 45 is pivoted in a bracket secured to the head of 60 the machine, and is provided with a tail piece 46 which prevents movement of the cam toward the right in Fig. 4. The cam is held in normal position by a spring 47 which will yield to allow the cam to move 65 toward the left. When the clamp is closed

by the movement of the cutter in cutting the material, the latch 40 snaps up in front of the shoulder 41 and holds the clamp in closed position. During the forward movement of the clamp carriage the head of the latch operating pin rides under the cam 45, and the cam yields to allow the head to pass freely by it. After the head of the pin has passed, the cam returns to its normal position. After the buttonhole has been sewed 70 the clamp is returned to its initial position, and during this movement the cam 45 acts to press the latch operating pin downward, thus disengaging the latch pin from the shoulder 41 and allowing the spring 36 to 75 open the clamp jaws. The opening movement of the clamp is limited by the engagement of the bearing for the pin 40 with a stop lug 48.

The clamp carriage 5 is in the form of a skeleton frame, as shown in Fig. 3, which is provided with bearing surfaces 49 arranged to move freely between bearing surfaces 50 formed on the under side of the frame 1 and on the upper side of the turret bracket 21 (Fig. 1). The carriage is also provided with bearing surfaces 51 which move freely between surfaces on the under side of the frame 1 and on supporting plates 52 secured to the frame (Fig. 4). The carriage is moved longitudinally or lengthwise of the buttonhole to shift the work from cutting to sewing position, to feed the work during the sewing, and to return the work to initial position after the buttonhole is completed, by a cam groove 53 formed in the under side of the cam carrying gear 31, which engages a roll carried on the upper end of a stud 54 secured in the carriage. The stud passes through a pivot block 55 arranged to slide in a slot 56 formed in the frame 1, and forms a pivot about which the carriage is swung to move the work clamp and work laterally in sewing along the sides of the eye of a buttonhole. The devices for 100 swinging the clamp carriage laterally comprise a lever 57 mounted upon the frame 1 and having one end pivotally connected to a block 58 which engages a slot 59 in the rear end of the carriage, and the other end provided with a roll engaging a cam groove 105 formed in the upper face of a gear 60.

The stitch forming devices comprise a straight-eye pointed upper needle 61 which is arranged to pass through the fabric at a 110 certain distance from the edge of the buttonhole, a curved-eye pointed under needle 62 arranged to pass through the buttonhole slit, and a looper 63 for taking a loop of thread from the upper needle and passing it over 115 the end of the under needle when it is in its retracted position, so that the under needle will pass up through the loop when it is advanced. The upper needle is eccentrically secured in a needle bar 65 mounted to re- 120

ciprocate through a rotary sleeve 66 and the under needle and looper are mounted on a rotary turret 88. The turret and sleeve are rotated during the sewing by mechanism operated from the gear 60 so that over-edge stitches are formed along the sides about the eye and across the end of the buttonhole cut in the material held by the work clamps.

The specific construction and mode of operation of the mechanisms for actuating the stitch forming devices and for actuating the gears 31 and 60 which relatively move the work clamp and stitch forming mechanism to sew about the buttonhole have not been fully described since they are not material to the improvements claimed herein, and are fully described in the application of which the present application is a division.

While it is preferred to employ the specific construction and arrangements of parts shown and described, it will be understood that this construction and arrangement is not essential to the broader features of the invention and may be varied and modified without departing therefrom.

Having explained the nature and object of the invention and specifically described one mechanism in which it may be embodied, what is claimed is:—

30 1. A buttonhole sewing machine, having, in combination, stitch forming mechanism and work holding clamp, mechanism for actuating the stitch forming mechanism and relatively moving the stitch forming mechanism and the work holding clamp to sew about a buttonhole, an independently actuated cutter, and connections between the cutter and clamp through which the entire closing movement of the clamp is effected by movement of the cutter toward the face of the work.

2. A buttonhole sewing machine, having, in combination, stitch forming mechanism, cutter and work clamp relatively movable to bring the parts into relative position for cutting or for sewing, means automatically closing the clamp, a latch for holding the clamp closed during the sewing, and means for releasing the clamp by the relative movement of the parts from sewing to cutting relation.

3. A buttonhole sewing machine, having, in combination, stitch forming mechanism, a cutter, a work clamp movable from cutting to sewing position, means for closing the clamp by the cutter, a latch for holding the clamp during the sewing, and devices for disengaging the latch by movement of the clamp at the completion of the sewing.

4. A buttonhole sewing machine, having, in combination, stitch forming mechanism and a work clamp relatively movable to bring the parts into relative position for receiving the work or for sewing, mechanism automatically closing the clamp, means for

latching the clamp closed, and devices for releasing the clamp operated by the relative movement of the clamp and stitch forming mechanism into work receiving position.

5. A buttonhole sewing machine, having, in combination, stitch forming mechanism, a cutter, a clamp movable from the cutter to the stitch forming mechanism, means for closing the clamp, a latch for holding the clamp closed, an actuator for releasing the latch, and a fixed cam past which the actuator is carried by the movement of the clamp from sewing to cutting position.

6. A buttonhole sewing machine, having, in combination, stitch forming mechanism and a work holding clamp, mechanism for actuating the stitch forming mechanism and relatively moving it and the work holding clamp to sew about a buttonhole, a cutter, a cutter carrying lever, mechanism actuating the lever to move the cutter toward and from the material, and connections between said lever and clamp through which the entire closing movement of the clamp is effected by movement of the lever toward the face of the work.

7. A buttonhole sewing machine, having, in combination, stitch forming mechanism, a work holding clamp, mechanism for actuating the stitch forming mechanism and relatively moving the stitch forming mechanism and the work holding clamp to sew about a buttonhole, a cutter mounted in fixed relation to the stitch forming mechanism, and connections between the cutter and the clamp for closing the clamp by movement of the cutter.

8. A buttonhole sewing machine, having, in combination, stitch forming mechanism, a work holding clamp, mechanism for actuating the stitch forming mechanism and relatively moving the stitch forming mechanism and the work holding clamp to sew about a buttonhole, a cutter, connections between the cutter and clamp through which the entire closing movement of the clamp is effected by movement of the cutter toward the face of the work, and connections for automatically opening the clamp after the completion of the sewing.

9. A buttonhole sewing machine, having, in combination, stitch forming mechanism, a work holding clamp comprising work supporting plates and cooperating pivoted clamp carrying arms, a rock shaft provided with arms bearing on the clamp carrying arms, mechanism for relatively actuating the stitch forming mechanism and work clamp to sew about a buttonhole, mechanism automatically actuating the rock shaft to close the clamp prior to the sewing, a latch for retaining the shaft in position during the sewing, and connections for releasing the latch after the completion of the sewing.

10. A buttonhole sewing machine, having,

in combination, stitch forming mechanism, a work holding clamp comprising work supporting plates and coöperating pivoted clamp carrying arms, a rock shaft arranged 5 above the clamp carrying arms and provided with arms the free ends of which bear on the clamp carrying arms, mechanism for relatively actuating the stitch forming mechanism and clamp to sew about 10 a buttonhole, mechanism automatically actuating the rock shaft to close the clamp prior to the sewing, means for holding the clamp closed during the sewing, and means for releasing the clamp after the sewing 15 is completed.

11. A buttonhole sewing machine, having, in combination, stitch forming mechanism, a cutter lever, a work holding clamp comprising work supporting plates and coöperating pivotally supported clamp carrying arms, a rock shaft, arms secured to the rock shaft bearing on the clamp carrying arms, a third arm on the shaft arranged to be engaged by the cutter lever, means for holding 20 the clamp closed during the sewing, and mechanism for actuating the cutter and relatively actuating the clamp and stitch forming mechanism to sew about a buttonhole.

12. A buttonhole sewing machine, having, in combination, stitch forming mechanism, a work clamp, feed mechanism for moving the clamp, a buttonhole cutter, cutter actuating means moving with the feed mechanism, and connections between the cutter and clamp for closing the clamp by the movement of the cutter.

13. In a buttonhole sewing machine, the combination with slit-cutting mechanism including coöperating cutting elements and a rock lever carrying one of said cutting elements, and a work holder having separable upper and lower clamping members and a controlling rock shaft therefor provided 40 with an arm arranged to be engaged by the rock lever.

14. In a buttonhole sewing machine, the combination with stitch forming mechanism, slit-cutting mechanism including a cutter 50 carrying lever mounted in fixed relation to the stitch-forming mechanism, and a traveling work holder having upper and lower clamping members separable to release and clamp the work, and a controlling rock shaft 55 for said work holder mounted to partake of the traveling movements of the same and provided with an arm, of clamp-closing means acting upon said arm of the clamp controlling rock-shaft and operatively connected with and operated by said cutter-carrying lever to effect the final closing of the work-holder substantially simultaneously with the slit-cutting action.

15. In a button hole sewing machine, the combination with slit-cutting mechanism in-

cluding coöperating cutting elements and a rock-lever mounted on a fixed fulcrum and carrying one of said cutting elements, and a work holder having upper and lower clamping members separable to release and 70 clamp the work and a controlling rock-shaft therefor provided with an arm, of clamp-closing means acting upon said arm of the clamp-controlling rock-shaft and having a positive connection with and actuated 75 by said rock-lever.

16. A button hole sewing machine, having, in combination, stitch-forming mechanism and a non-rotary work-holding clamp, mechanism for actuating the stitch-forming 80 mechanism and relatively moving the stitch-forming mechanism and the work-holding clamp to sew about a buttonhole, an independently actuated non-traveling cutter, and connections between the cutter and clamp 85 for closing the clamp by movement of the cutter toward the face of the work.

17. A buttonhole sewing machine, having, in combination, stitch-forming mechanism and a work-holding clamp, mechanism for 90 actuating the stitch-forming mechanism and relatively moving it and the work-holding clamp to sew about a buttonhole, a cutter, a cutter-carrying lever mounted in fixed relation to the stitch forming mechanism, mechanism actuating the lever to move the cutter toward and from the material, and connections between said lever and clamp 95 for closing the clamp by movement of the lever toward the material.

18. A buttonhole sewing machine, having, in combination, stitch-forming mechanism and a work-holding clamp, mechanism for actuating the stitch-forming mechanism and relatively moving it and the work-holding 105 clamp to sew about a buttonhole, a cutter comprising coöperating cutting elements, a lever mounted in fixed relation to the stitch forming mechanism carrying one of said cutting elements, mechanism for actuating 110 the lever to move said cutting element toward and from the material, and means for establishing operative connection between said lever and the work-clamp whereby the latter is closed upon the material.

19. A buttonhole sewing machine, having, in combination, stitch-forming mechanism and a work-holding clamp, mechanism for actuating the stitch-forming mechanism and relatively moving the stitch-forming mechanism and the work-holding clamp to sew 120 about a buttonhole, a cutting device mounted in fixed relation to the stitch-forming mechanism and mounted independently of the work-holding clamp and actuated independently of the stitch-forming mechanism, and connections between the cutting device 125 and the clamp for closing the clamp by movement of the cutter toward the face of the work,

20. In a buttonhole sewing machine, in combination, stitch forming mechanism, a work-holder having upper and lower clamping members separable to admit the work, a controlling rock-shaft therefor provided with an arm, slit-cutting mechanism comprising a cutting element, a pivotally mounted carrier therefor mounted in fixed relation to the stitch forming mechanism, 10 actuating means for said carrier, and means independent of said actuating means for establishing operative connection between said arm of the clamp-controlling rock-shaft and said carrier for effecting the final closing of the work-holder substantially simultaneously with the slit-cutting action. 15
21. In a buttonhole sewing machine, in combination, a work-holder having upper and lower clamping members separable to admit the work, a controlling rock-shaft therefor provided with an arm, slit-cutting mechanism comprising a cutting element, a carrier therefor, a fixed fulcrum for said carrier mounted substantially parallel with said controlling rock-shaft, actuating means for said carrier, and means independent of said actuating means for establishing operative connection between said arm of the clamp-controlling rock-shaft and said carrier for effecting the final closing of the work-holder substantially simultaneously with the slit-cutting action. 25
22. A buttonhole sewing machine, having, in combination, stitch-forming mechanism, a work-holding clamp, mechanism for actuating the stitch-forming mechanism feed mechanism for relatively moving the stitch-forming mechanism and the work-holding clamp to sew about a buttonhole, a cutter, cutter operating mechanism connected with the feed mechanism, connections between the cutter and clamp for closing the clamp by the cutting movement of the cutter, and means timed in its action by a connection with a moving member of the machine for automatically opening the clamp after the completion of the sewing. 35
23. A buttonhole sewing machine, having, in combination, stitch forming mechanism, a work clamp, a feed cam for moving the clamp, a buttonhole cutter, a cutter operating cam moving with the feed cam, and clamp closing means operated by the cutter operating cam. 45
24. A buttonhole sewing machine, having, in combination, stitch forming mechanism, a work holding clamp, a feed cam for moving the clamp lengthwise of the buttonhole, a cutter lever, operating means therefor connected with the feed cam, and connections for closing the clamp by the lever. 55
25. A buttonhole sewing machine, having, in combination, stitch forming mechanism, a traveling work clamp movable into work receiving and into sewing position, mechanism automatically closing the clamp when in work receiving position, an independent latch for holding the clamp closed during its travel, and means for operating the latch to release the clamp by the movement of the clamp from sewing to work receiving position after the completion of the sewing. 60
26. A buttonhole sewing machine, having, in combination, stitch forming mechanism, a traveling work clamp movable into work receiving and into sewing positions, mechanism automatically closing the clamp when in work receiving position, independent latching means for holding the clamp closed during its travel, and a fixed unlatching device mounted to permit free forward movement of the latching means and to operate said means and release the clamp during the return of the clamp from sewing to work receiving position. 65
27. A buttonhole sewing machine, having, in combination, stitch forming mechanism, a clamp carriage, mechanism for moving the clamp carriage lengthwise of the buttonhole before, after and during the sewing, work clamping means on the carriage comprising upper clamping members, a rock shaft and connections through which the clamping members are closed by rotation of the rock shaft, mechanism for automatically 75
- rocking the shaft to close the clamping members, a latch for latching the rock shaft and clamping members in closed position, and an unlatching device mounted on a fixed part of the machine to permit free forward movement of the latch and to operate the latch and release the clamp by the return movement of the carriage after the completion of a buttonhole. 80
